IRONING CORD SUPPORT

Palmer W. Rom, Cudahy, Wis., assignor of one-half to Fritz Mynders, Milwaukee, Wis.

Application April 9, 1937, Serial No. 135,891

1 Claim. (Cl. 248—51)

The invention relates to ironing cord supports.

The object of the invention is to provide a support for the conductor cord of an electric iron while ironing material on a board and which through the action of the weight of the cord itself will keep the cord out of the way of the work and will offer substantially no resistance to the shifting of the cord relative to said support. More particularly the invention is designed to provide a support for mounting on an ironing board and carrying a roller guide over which the cord works and moves of its own weight, the support having a portion cooperating with the roller to prevent the cord working off of said roller, the roller preferably being mounted at a less height above the board than the height of the connection of the cord with the terminal member secured to the iron so that the cord slopes downwardly from its point of connection with the iron to said roller and preferably operates with some slack below said roller so that the weight of this slack cord acts to take up slack in the cord between said iron and support.

The invention further consists in the several features hereinafter set forth and more particularly defined by the claim at the conclusion hereof.

In the drawing:

Fig. I is an end elevation view of a device embodying the invention showing it in operating position;

Fig. II is a side elevation view of the device;

Fig. III is a plan view of the device.

Referring to Fig. I of the drawing, the numeral 5 designates a portion of an ironing board, 6 an electrically heated iron, 7 a conductor cord for supplying heating current to said iron, 8 a terminal member for said cord detachably connecting it with said iron, and 9 the improved conductor cord support.

The cord support 9, shown in detail in Figs. II and III is formed from a steel or other suitable metal wire of suitable gauge which is bent to provide a base portion here formed by a straight section 10, a bent portion 11, and angularly bent portions 12 and 13 which through the bent portion 11 are spaced from the section 10 so that the device may be slipped over the side edge of an ironing board 5 and be clamped thereto by its own resiliency, the section 10 engaging the top of the board while the parts 12 and 13 engage the bottom of the board. The end 14 of the part 13 may also be bent to engage beneath a screw in the bottom of the board if desired.

An upright section 15 extends from the section 10 and is preferably inclined outwardly relatively to the board and its upper end is formed to provide a support for a flanged roller cord guide member 16. For this purpose the upper end of the section 15 curves downwardly at 17, is then bent around or back on itself at 18, and then curved backwardly at 19 and thence downwardly at 20 and then bent forwardly to provide a roller spindle 21 upon which the roller 16 is loosely mounted, said spindle extending either parallel to the straight section 10 or slightly inclined relative thereto. The bent portion 17 extends downwardly to a slight distance below the flanged end 22 of the roller so that while the spindle 21 may be sprung slightly to mount the roller thereon, said bent portion 17 will act as a stop to limit the lengthwise movement of the roller on its spindle. The roller 16 has sufficient endwise movement on the spindle to provide a space 23 between its front end and the bent portion 17 so that the cord 7 may be passed through this space and onto said roller between the flanged ends thereof. The downwardly bent portion 20 serves as a back stop for the roller 16, and the part 24 of the section 15 adjacent the roller acts as guard to permit the cord to be moved at a considerable angle relative to the axis of the roller without coming off of the roller.

With the device mounted on the board at any convenient location but usually on the side edge of the board opposite the ironer, the cord 7 is slipped on to the roller and its slack portion 25 is allowed to hang down over the side of the board, and then as the operator moves the iron 35 6 back and forth over the work, the cord will move back and forth over the roller, the weight of the slack cord keeping the cord on the roller, and the drop of the cord from the point of its connection with the terminal member 8 to said 40 roller also assisting in giving the cord a free movement. It will, therefore, be noted that the slack between the iron and the support 9 is automatically taken up, and this will keep the cord above the work and out of the way of the work 45 and the iron. It will also be noted that the support may be turned to various angular positions relative to the ironing board to suit the operator's convenience in ironing. While any suitable conductor cord may be used, a rubber covered cord or a fairly stiff fabric covered cord is 50 recommended.

The support for the roller may, of course, be made in many different ways, but the one herein shown has advantages of simplicity, low produc- 55

tion cost, light weight, and ease of assembly of the parts though I desire it to be understood that this invention is not to be limited to the details of construction hereinbefore set forth except in so far as such limitations are included in the claim. 5

What I claim as my invention is:

A conductor cord support having means for mounting it on an ironing board and having an upright section with a curved end bent back on itself and then bent forwardly to provide a roller spindle and guard, and a roller mounted on said spindle. 5
